(57) **CLAIM**

The ornamental design for a body for wearable air conditioner, as shown and described.

DESCRIPTION

FIG. 1 is a front perspective view of a body for wearable air conditioner showing our new design; FIG. 2 is a back perspective view thereof; FIG. 3 is a front view thereof; FIG. 4 is a back view thereof; FIG. 5 is a left side view thereof; FIG. 6 is a right side view thereof; FIG. 7 is a top plan view thereof; FIG. 8 is a bottom plan view thereof; FIG. 9 is an exploded perspective view of an environment of use of the body for wearable air conditioner; and, FIG. 10 is an exploded perspective view of another environment of use of the body for wearable air conditioner. The broken lines depict portions of the body for wearable air conditioner that form no part of the claimed design. The broken lines in FIGS. 9 and 10 show portions of the body for wearable air conditioner and the environmental structure that form no part of the claimed design.
